(57) **CLAIM**

An ornamental design for a cigar glass, as shown and described.

DESCRIPTION

FIG. 1 is a top, front isometric view of a cigar glass showing my new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The present invention relates in general to beverage containers and, in particular, to a beverage container that can also support and/or hold a cigar or cigarette.
